United States Patent Office.

HENRY F. HOLT, OF FREDONIA, NEW YORK, ASSIGNOR TO HIMSELF, T. C. ABBOTT, AND F. B. PARKER.

Letters Patent No. 71,304, dated November 26, 1867.

IMPROVEMENT IN FASTENING TOPS TO BUGGIES.

The Schedule referred to in these Letters Patent and making part of the same.

TO ALL WHOM IT MAY CONCERN:

Be it known that I, HENRY F. HOLT, of Fredonia, in the county of Chautauqua, and State of New York, have invented a certain improved Fastening for Securing Tops to Buggy-Seats; and I do hereby declare that the following is a full, clear, and exact description thereof, reference being had to the accompanying drawing, making a part of this specification, in which—

Figure I is a front elevation of buggy-seat and top.

Figure II, a side elevation of same; and

Figure III, a cross-section on line 1-2 of Fig. I.

Buggy-tops are now commonly constructed with a base-rail of iron, to which the bows supporting the covering are attached. This base-rail is shaped to correspond with the upper edge of the buggy-seat, to which it is secured, in some instances, by bolts or screws, and in others by lock-fastenings, which permit the ready connection of the buggy-top to, or its disconnection and removal from, the buggy-seat.

My invention relates to a fastening device of the kind last mentioned, and consists in securing the buggy-top to the seat by horizontal and vertical shanks or hooks projecting from the under side of the base-rail, and entering corresponding sockets fastened to the sides of the buggy-seat, acting in combination with each other, and a spring-shank hook and socket at the back of the seat, to secure the top firmly to the seat against upward and backward and forward strains.

Like letters refer to like parts in each of the figures.

A represents the buggy-seat, of any common form or construction; B represents the base-rail of the top, to which the bows supporting the covering are attached in a common manner. An extension, C, of the seat-back may be also attached to the base-rail in a common manner. D D represent the horizontal sockets formed in the ends of iron plates, securely fastened by screws to the sides of the seat near the front thereof, the sockets projecting slightly beyond the rim of the seat. E E represent the vertical sockets formed and secured similar to sockets D to the sides of the seat, near the back thereof, and also projecting slightly over the rim of the seat in line with sockets D. F represents the vertical socket applied to the back of the seat, at the centre thereof, in the same manner as sockets D and E are applied to the sides. G G represent the shanks projecting from the under side of the base-rail and entering the horizontal sockets D. H H represent the vertical shanks projecting from the under side of the base-rail and entering the sockets E. I represents the shank-hook projecting from the under side of the base-rail at the back centre thereof, and entering the socket F. J represents a spring key riveted to the back of the base-rail and catching between the base-rail and a shoulder, J', formed on the socket-plate F, and thereby locking the shank-hook I in its socket F. The individual action of the horizontal shanks G, when entered in their sockets, will be to secure the top against an upward strain applied at the front thereof, while that of the vertical shanks H will secure it against a backward strain, and that of the shank-hook I will secure it against a forward and upward strain, and their combined action will be to secure the top firmly to the seat against any and all strains to which it may be subjected. The disconnection and removal of the top from the seat is effected by first pressing the spring key J out from its engagement with the shoulder J', and then raising the top slightly at the back, sufficient to withdraw the vertical shanks, when a short backward movement will withdraw the horizontal shanks, and the disengagement will be complete.

The operation of connecting the top to the seat is simply the reverse of that just described.

Having thus fully described my invention, what I claim, and desire to secure by Letters Patent, is—

The described arrangement of the horizontal and vertical shanks and sockets at the sides of the top and seat, in combination with the shank-hook and socket and spring key at the back of the seat, in the manner and for the purpose set forth.

HENRY F. HOLT.
